UNITED STATES PATENT OFFICE.

WILLIAM SOUTHERN BRICE, OF LIVERPOOL, COUNTY OF LANCASTER,
ENGLAND.

FLOATING ELEVATOR.

SPECIFICATION forming part of Letters Patent No. 293,625, dated February 19, 1884.

Application filed May 18, 1883. (No model.) Patented in England October 7, 1882, No. 4,782, and in Belgium October 8, 1883, No. 62,817.

To all whom it may concern:

Be it known that I, WILLIAM SOUTHERN BRICE, of Liverpool, in the county of Lancaster, England, have invented certain new and useful Improvements in Floating Elevators, of which the following is a specification.

Elevators for elevating grain out of ships' holds differ from those used on land in this respect, that the distance between the points from and to which the grain has to be elevated is constantly varying. To enable one to overcome this, numerous expedients—such as lazy-tong frames, loop-lines on the belt of pulleys for taking in that part of the length of belting not wanted, double elevators in which one elevator elevates into another, suspension-elevators which are suspended from above and are lowered down into the hold, but have a spout from the top, up to which all the grain has to be elevated, and other plans of a like nature, having either very complicated arrangements for taking in the slack, or of one part feeding into another part—have been adopted. Now, my elevator differs from these, in that while the elevator consists of a single chain of buckets without separate legs or subsidiary elevator, it yet elevates the grain to any required point, instead of to a lower height, as the elevator descends. It is best described by aid of the accompanying drawings, in which—

Figure 1 is a sectional elevation of an elevator fixed to its barge, and of the ship's hull, in which the elevator is seen at work; Fig. 2, a section of the elevator-band casing with actuating-pulleys; Fig. 3, a front elevation of same; Fig. 4, a section of casing, showing pulleys with the belt of buckets removed; Fig. 5, a side elevation of head-stock of elevator; Fig. 6, a section of same, showing friction-rollers, through α ; Fig. 7, a plan of head-stock and adjacent parts; Fig. 8, a view of elevator stowed away on cradle fore and aft of barge, for removal from one dock or ship to another.

In these A is the ship from which the grain has to be elevated; B, barge with elevator permanently fixed thereon; C, standard or column supporting elevator. In the drawings this is shown as a cast-iron pillar, but may be made

of wrought-iron lattice-work in any convenient or suitable manner to make it lighter or more stable. D is the engine for driving the elevator; E, the boiler for supplying steam to engine. F F are winches for raising, lowering, and also retaining the elevator proper in its required position when at work; G, the elevator proper, constructed as follows:

Within frame-work g are mounted on suitable shafts the pulleys g' , g'' , g^3 , and g^4 . Over these is passed a belt or chain, g^5 , on which is mounted any required number of buckets, g^6 . The bearings of the shaft carrying the pulleys g^4 are made adjustable. A carriage, g^7 , carries the tension-pulleys g^8 , and is provided with the runners g^9 . This carriage g^7 is mounted on the shaft h , (on which the driving-pulleys h' and pulleys g^3 are keyed,) and works freely within the elevator-casing.

H H are slots in the framing g , in which the shaft h slides freely.

I is the hopper or spout, into which the grain falls at spout i^3 , for delivering the grain from elevator onto a traveling band, J, for conveyance to warehouse or other place. The hopper or spout I may consist of a series of tubes or pipes passed one within the other, as shown at Fig. 1; but a more convenient form is shown at Figs. 2 and 3, in which one side of the tube consists of a number of doors or flaps, i , hinged or pivoted at the center and placed one above the other, as shown. By this arrangement an opening can be provided at any point in the spout I by simply pushing or tilting the door or flap i back against the side of the elevator, as shown at i' in Fig. 2. The movable side piece, i^2 , is then placed in position, as shown in dotted lines, to prevent the grain from spreading and passing off the sides of the door i . This movable side piece, i^2 , is so formed that it clips the side of the spout or hopper I, and is supported by the pin i^4 .

Instead of placing the spout I and conveyer or traveling band J, as shown in Fig. 1, so as to carry the grain over the vessel A, which is being unloaded, the spout may be so placed as to discharge onto a traveling belt or conveyer placed below the frame-work cradle K, and held in position by a pulley attached thereto

at one end and attached to the head of the column C at the other. By such an arrangement as this the grain from the vessel could be discharged by a slide onto another flat or barge 5 lying alongside that on which the elevator is fixed. This, however, can be arranged as circumstances may require, and is not shown in the drawings. The sides of the elevator G are provided at the bottom with the slits g¹⁰, for 10 the admission of grain to the buckets g⁶.

K is the horizontal frame-work cradle or jib for supporting the elevator proper, G, and is so connected at h to the head-stock, by means of vertical trunnions or journals c', that it permits of the framing K being raised or lowered to any suitable angle to suit the requirements 15 of the elevator proper, G, and also allows the elevator to be stowed away upon the said frame-work cradle when actually not working.

20 Between the sides of the framing K are mounted a series of rollers, k', for supporting the elevator when stowed away. The frame-work K is carried in the bracket k², the upper portion, k³, of which is prolonged to serve 25 as a tension-post, to which the tension-rods k⁴ are attached by means of the adjustable links k⁵. The lower end of the bracket k² is mounted on or coupled to the trunnions c' of the head-stock c, which permits of the framing being 30 placed at any required angle.

On the framing K are mounted the pulleys k⁶ and k⁷, (for adjusting and retaining the elevator in position,) and also the bearings k⁸, for carrying the shaft h.

35 To compensate for the varying width of ships and the distance of the hatchway from their sides, I may arrange a telescopic slide at the outer end of the frame-work K, so that the end of K may at all times be brought as nearly 40 as possible over the center of the hatchway. This I do not show in the drawings, as I make no specification for such a modification of the frame-work cradle.

In order to allow the elevator G and framing K to be swung or moved radially round to 45 any position, I arrange the top of the pillar or column C as follows: On the top of the column C is mounted a head-stock, c, provided with the trunnions c', also the bearings for 50 carrying the small rope-pulleys c² c³. Through the center of the head-stock c is passed (and screwed into the column C) the vertical pin c⁴, on which the head-stock c rotates, below the head-stock c, and resting on the top of the column 55 is the ring c⁵, containing the anti-friction rollers c⁶. This ring c⁵ is also retained in position by means of the pin c⁴, and allows the head-stock c to revolve freely. The head-stock c and ring c⁵ are secured onto the top of 60 the column by means of the nut and washer c⁷.

The mode of action is as follows: The elevator and framing are swung round so as to be transversely to the barge B, which has been 65 previously placed abreast the hatch on the off side of the ship A to be discharged, and the elevator proper, G, is projected along the frame-work cradle K, (the end of which is over

the hatchway) until the elevator proper, G, is drawn (by means of a rope, L, and block attached to the ship's rigging, said rope L serving 70 as a stay for steadyng the elevator when at work) into the position shown at Fig. 1. The elevator is pivoted on the driving-shaft, and is retained in any desired position by means of the ropes M and N, which pass over the pulleys c² c³ h⁶ h⁷ from the winches F, and are attached to the elevator, respectively, at m and n, and after it has been guided into the hatchway it is then set in motion, and gradually sinks 75 as the bulk cargo is elevated and discharged 80 from the buckets into the hopper I. Motion is conveyed to the elevator-buckets g⁶ from engine D through pulleys O and chain-wheels P and P' by means of belts or chains Q and R, to pulleys h⁸ and g⁷, thence to the buckets on 85 belt or chains g⁶. The shaft h, passing through the slot H, and carried in bearings k⁸ on the frame-work K, permits the elevator G to be raised or lowered at pleasure without affecting the driving, and whatever position the elevator may assume, the chain of buckets is kept perfectly tight by being passed over the tension-pulleys g⁸ on the carriage g⁷, (which is also attached to the shaft h,) and pulleys g⁹, as 90 shown in Fig. 2. The blocks and ropes shown at S are for adjusting and retaining the horizontal frame-work cradle K. When the discharging of the grain is completed, the elevator is raised out of the hatchway, and by means of the rope M is drawn onto the framing K, which is then moved round by head-stock c until the elevator and framing are in a longitudinal position with regard to the barge, when the ropes S are slackened, and the elevator and framing lowered into position 95 shown at Fig. 8. The barge may then be moved alongside the next vessel to be discharged.

I am aware that an endless chain has been connected directly to a stationary tower in such 110 manner as to swing both vertically and horizontally about the same, and also that an endless-chain elevator has been connected with adjustable supports of various kinds. I believe myself, however, to be the first to attach an 115 elevator adjustably or movably to the end of a frame which is in turn arranged to swing both vertically and horizontally about a stationary tower or standard. I also believe myself to be the first to provide an endless-chain 120 elevator arranged to slide and swing bodily about a driving-pulley which acts upon the chain at an intermediate point in its length.

I claim as my invention—

1. In a floating elevator, the vertical tower 125 or standard, the frame arranged to swing both vertically and horizontally upon the said standard, and the endless elevator attached to and adjustable vertically with respect to the overhanging end of the frame, all combined substantially as described.

2. In a floating elevator, the combination of 130 the pillar or standard, a supporting-frame connected to said standard in such manner as to

- swing both vertically and horizontally, and an elevator, substantially as described, connected to the outer end of said frame, and adjustable vertically thereon by means substantially as 5 described.
3. In a floating elevator, the combination of the tower or standard, the frame movable vertically and horizontally about the same, and the elevator connected to the end of said frame 10 by means substantially as described, adapted to permit the elevator to be raised and lowered, and also varied in inclination with respect to the supporting-frame.
4. In a floating elevator, the combination, 15 with a fixed supporting-frame, K, of an upright elevator having an endless chain of buckets, substantially as described, said elevator being movable in a vertical direction with respect to the frame, and driving-pulleys h', for 20 said elevator, mounted on the supporting-frame, whereby the vertical adjustment of the elevator is permitted without affecting the action of the driving mechanism.
5. A floating elevator formed of a floating 25 base, a column, a frame-work cradle or jib jointed to same, so that it can stand at any required angle, and an elevator-frame hung from the said jib, but capable of being stowed away, lying flat upon said jib, without disconnecting 30 the driving mechanism, substantially as described.
6. In a floating elevator, the combination of a column, C, a frame, K, pivoted to same, so as to be swung to almost any angle, with the 35 axis of said column horizontal or vertical, and an elevator, G, pivoted to said frame, so as to hang to any desired angle with the vertical, substantially as described.
7. The combination of the frame K, the shaft 40 h, the elevator G, capable of partial rotation on the shaft h, and also capable of being raised or lowered while the shaft remains stationary, and elevator driving-pulleys mounted on said shaft, substantially as described.
- 45 8. The combination of an elevator, G, formed of a slotted frame-work, belt or chain of buckets, and the requisite pulleys and driving-shaft h, working in slot of frame, with carriage g' and system of pulleys thereon carrying the belt 50 of buckets, and driving same without any other contact than a sliding or fanning one with the frame-work.
9. The slotted elevator G, suspended by chain or rope N, but free otherwise to descend, 55 and driven by shaft h, passing through the longitudinal slot in the elevator-frame.
10. The combination of slotted elevator-frame G, the chain of buckets, the driving-shaft h, passing through the slot, and the carriage g', carrying the driving and tension pulleys, and carried itself by the shaft h.
11. In an elevator-frame, the driving mechanism consisting of a driving-axle driven by wheels h', and carrying driving-wheels g³, and a carriage, g', which in turn, on spindles in 65 suitable bearings, carries tension-pulleys g⁸ and runners g⁹.
12. In combination with an elevator, the driving-pulleys g³, carrying-pulleys g' and g⁴, tension-pulleys g⁸, and deflecting-pulleys g², 70 substantially as and for the purposes specified.
13. In an elevator, the combination of the upright endless chain of buckets g⁶, mounted in a vertically-adjustable frame, the supporting-pulleys g', guide-pulleys g⁴, pulleys g², arranged to deflect the chain inward below the pulleys g', and the spout i³, entering between the pulleys g' and g², as described and shown, whereby the delivery of the grain from the buckets into the spout is insured. 75
14. In combination with an upright elevator having an endless chain of buckets, as described, a spout or hopper, I, affixed to the front of said elevator, and a series of pivoted doors, i, mounted in the front of said spout or 80 hopper, and each adapted for adjustment as a spout or deflector, whereby the delivery of the grain may be effected at any required point in the length of the spout or hopper.
15. In combination with the frame K, the 85 elevator containing an endless chain of buckets supported upon said frame, and adjustable thereon, both as to height and inclination, and a telescopic hopper or chute having one end affixed to the upper end of the elevator, and the opposite end affixed to the supporting-frame, whereby the delivery of the grain at a fixed point is secured, notwithstanding variations in the position of the elevator. 90
16. The combination of the pivoted elevator-frame G, the guiding-ropes M and N, attached to opposite ends of same, and leading to winches, and the guide-pulleys k⁷ and k⁶, placed near opposite ends of the horizontal or oblique-lying frame K, carrying said elevator-frame, all for the purposes specified. 100
17. The pivoted head-stock c, free to rotate horizontally on the column C, and carrying pulleys c'' and c², and the trunnions c', for pivoted bracket k² and its frame or jib K, substantially as specified. 105
18. The frame-work cradle or jib K, formed with a straining-post, k³, and tie-rods k⁴, and a bracket, k², immediately below the straining-post, fitted with bearings, so that the said jib can freely oscillate on the journals or trunnions of said bearings, for the purposes described. 110
